UNITED STATES PATENT OFFICE

FREDERICK W. C. NEUNER, OF CONNERSVILLE, INDIANA, ASSIGNOR TO INDIANA LAMP CORPORATION, OF CONNERSVILLE, INDIANA, A CORPORATION

LAMP BODY AND DOOR FASTENING

Application filed December 19, 1927. Serial No. 241,020.

This invention relates to a body and door fastening construction suitable for head lamps and the like, although not solely confined thereto.

5 The chief object of this invention is to provide a construction which eliminates from the face or edge of the door any unsightly or locking device. The foregoing object is accomplished by having the two cooperating 10 catch portions and associated parts, one being mounted upon the door and the other upon the casing positionable within the same when in assembled relation and having a relatively small rearwardly exposed portion 15 provided with a tool-engageable arrangement for actuation.

The full nature of the invention will be understood from the accompanying drawings and the following description and 20 claims:

In the drawings Fig. 1 is a central sectional view of one form of the invention. Fig. 2 is a front elevation of the upper portion of Fig. 1 with the invention shown 25 dotted. Fig. 3 is a bottom plan view of the latch shown in Figs. 1 and 2. Fig. 4 is a central sectional view of a modified form of the invention. Fig. 5 is a front elevation of the parts shown in the upper portion of 30 Fig. 4. Fig. 6 is a similar view of the parts shown in the lower portion of Fig. 4. Fig. 7 is a perspective view of the combination catch and guide shown in Figs. 4 and 6.

In Figures 1 to 3 inclusive, 10 indicates a 35 casing having a peripheral shoulder portion 11. Within the casing is supported a reflector 12 having an outwardly directed flange 13 which as herein shown, abuts against as well as bears upon the inturned flange 14 of the 40 casing. The closure 15 bears on an annular cushion and sealing member 16 and a door rim 17 bears on the same at 18 and includes an inturned annular bead or bearing portion 19 for engagement with the casing shoulder 45 for limiting the inward movement of the closure and rim. All of the aforesaid is standard construction in the head lamp art and any other additional parts may be added thereto to complete the lamp construction.

50 The present invention relates to a rela-

tively non-exposed casing and door fastening construction. In the form of the invention illustrated in Fig. 1, three of the aforesaid latching constructions are employed, of which one is shown, said constructions being 55 arranged in spaced relation relative to each other. Each construction includes a drawn socket 20 formed in the rear end of the casing for receiving the tapered head 21 of a screw bolt 22 having a bifurcated or enlarged end 23, the exposed head 21 being suitably fashioned for tool engagement. A strap or bar 24 has an angular end 25 apertured at 26 and herein suitably threaded for bolt reception. Interposed between the angular end 25 and the casing and concentric with the drawn portion 20 of the casing opening and seated about and upon the same is a coil spring 27 for normally projecting the bar 24 forwardly and into latch releasing position. The opposite end of the bar 24 includes an angular portion 28, the parallel portion 29 and a locking portion 30. Riveted to the door rim by suitable number of rivets, and herein one is disclosed and indicated by 70 the numeral 31, is a catch having the body portion 32 and a hook or catch retaining portion 33 engageable by the catch portion 30 of the strap when the threaded bolt 22 is turned inwardly to draw the strap rearwardly. 75

It has been customary to mount lamp closure by partially rotating the same and the member 32 permits of such operation, to wit, the locking portion 33 includes a pair 85 of parallel extensions 34 and 35 which serve as guides, the latter being elongated and serving as a stop and extending angularly of the portion 34 is an inclined portion 36 so that in the rotational seating movement of the rim upon the casing the strap member will engage the inclined portion 36 in the partial rotation of the rim, seat in the groove thus formed and be prevented from further lateral movement relative to the rim by the elongated portion 35. The aforesaid portions 33, 34 and 35 form a pocket which receives the locking portion 30 of the strap. In the present form of the invention the 90 casing flange 14 is slotted as at 40 and the 95 100
